UNITED STATES PATENT OFFICE

FRANK BRASS, NOAH OTTEN, AND GEORGE C. TOLAND, OF RAVEN, COLORADO

APPARATUS FOR WOOD DISTILLATION

Application filed March 15, 1927. Serial No. 175,568.

This invention relates to apparatus for wood distillation and it is an object of the invention to provide an apparatus of this kind which is especially designed and adapted for use in connection with pitch-pinion timber and wherein the timber in its treatment is subjected to dry heat.

- It is also an object of the invention to provide an apparatus of this kind comprising a retort adapted to contain timber to be treated together with heating chambers arranged at opposite sides of the retort, said chambers being free of communication with the retort.
- 15 It is a further object of the invention to provide an apparatus of this kind with means whereby the products of distillation are readily collected.

The invention consists in the details of construction and in the combination and arrangement of the several parts of our improved apparatus for wood distillation whereby certain important advantages are attained and the device rendered simpler, less expensive and otherwise more convenient and advantageous for use, as will be hereinafter more fully set forth.

- The novel features of our invention will hereinafter be definitely claimed.
- 30 In order that our invention may be the better understood, we will now proceed to describe the same with reference to the accompanying drawings, wherein:—

Figure 1 is a view in top plan and of somewhat a diagrammatic character illustrating an apparatus constructed in accordance with an embodiment of our invention;

Figure 2 is a view partly in vertical section and partly in side elevation and also of somewhat a diagrammatic character of the apparatus as herein disclosed;

Figure 3 is an enlarged transverse sectional view taken substantially on the line 3—3 of Figure 1;

45 Figure 4 is a fragmentary sectional view taken lengthwise of the cooling or condensing trough as herein disclosed, certain of the parts being in elevation;

50 Figure 5 is a sectional view taken substantially on the line 5—5 of Figure 4;

Figure 6 is a sectional view illustrating the discharge end portion of a drip pipe and the parts associated therewith;

Figure 7 is a sectional view of the tank X illustrating the inner construction thereof. 55

As disclosed in the accompanying drawings, F denotes a furnace the walls of which are preferably constructed of fire clay, said furnace as herein disclosed having a flat bottom wall 1 and an arcuate top wall 2 and in 60 communication with the rear portion of the furnace is a flue 3.

The front end wall 4 of the furnace F at its central portion is provided with an opening 5 through which extends a retort R cylindrical in cross section, the walls of which being preferably of metal. This retort R is of a length to extend from a point slightly in advance of the front wall 4 of the furnace F to a point slightly in advance of the rear 70 wall 6. The portion of the retort R within the furnace F has its lower portion snugly engaged within a groove or channel 7 extending lengthwise of the bottom wall 1 of the furnace and herein disclosed as provided in 75 a raised portion 8 of such bottom wall.

The top portion of the retort R has close contact with the top wall 2 of the furnace F whereby heating chambers 9 are provided within the furnace F at opposite sides of the 80 retort R and the rear portion of each of said chambers having requisite communication with the flue 3 as clearly illustrated in Figure 1 of the accompanying drawings. Each of the chambers 9 at its forward portion has 85 the fuel charging opening 10 in communication therewith through the outer side wall thereof, which provides means for introducing the necessary fuel into the chamber 9.

The fuel to heat the retort is preferably 90 disposed within each of the chambers 9 at the lower portion of the retort R immediately adjacent thereto to maintain a high temperature within the retort.

The retort R is of such dimensions as to 95 permit entry therein of a car loaded with pinion timber to be treated, such car C riding on the trackway T arranged within the lower portion of the retort. This trackway T is in continuation of an exterior trackway T' 100

whereby the loaded car may be readily carried into the retort R or moved therefrom. As is illustrated in Figure 1, the trackway T' is provided with a branch B for a purpose to 5 be hereinafter more particularly referred to.

When a loaded car C is within the retort R, the outer or entrance end of the retort is closed by a door D.

In communication with the forward portion 10 of the retort through the bottom thereof and the bottom wall 1 of the furnace F is a carry-off pipe 11 preferably having an interior diameter of twelve inches. This pipe, as herein disclosed, extends away from the retort 15 on a downward incline and discharges into a tank X of desired capacity and preferably of a capacity of fifty-four gallons. The lower portion of this tank X has in communication therewith a drip pipe 12 adapted to discharge 20 into a container 14.

In communication with the upper portion of the tank X is an elongated pipe 15, in practice having an interior diameter of three inches. This pipe 15 extends through a 25 trough 16 adapted to be filled with cold water surrounding the portion of the pipe 15 within the trough. At separated points therealong are the drip pipes 17, 18, 19, 20, 21 and 22 each of which discharges into a pail 23.

30 The portion of the pipe 15 within the trough 16 is supported by the blocks 24 in spaced relation to the floor 25 of trough 16, thus assuring effective surrounding of the pipe 15 by the water within the trough. The 35 drip pipes hereinbefore referred to are each preferably of an interior diameter of one inch.

It is also to be understood that the door D when closed hermetically seals the outer or entrance end of the retort R.

40 In practice, the pinon timber to be treated is split and loaded on a car C and the loaded car is then pushed within the retort R, after which the door D is closed. The fires within the chambers 9 are then started and the 45 temperature within the retort raised to the desired degree. The action of the heat on the timber results in a distillation of a heavy gas which passes out through the carry-off pipe 11 to the tank X. Tar and other heavy 50 residues pass off through the drip pipe 12 into a receptacle 26 carried by the discharge end portion of the pipe 12 and into which said pipe 12 slightly extends. By this arrangement the tar or other residues before 55 overflowing from the receptacle 26 into the pail 14 forms a liquid seal for the discharge end of the drip pipe 12.

The vapors passing off from the tank X are 60 carried through the pipe 15 which is surrounded with cold water and thereby operates as a condenser. The first drip pipe 17 carries off a liquid consisting chiefly of pyroligneous acid and a small amount of tarry residue which is readily separated by settling. The pipe 18 carries off a purer form

of the acid, as acetic acid, while pipe 19 carries off acid and a small amount of very light oil which will not mix and is, therefore, easily separated by drawing the acid away from the oil. The pipe 20 carries off the oils while pipes 21 and 22 carry off the creosote, alcohol and other by-products.

After the pinon timber has been properly distilled, the car C with the resultant load of charcoal is withdrawn from the retort and preferably carried off to the branch B or beyond such branch so that a second car which has in the meantime been loaded with the desired split timber can be easily run into the retort and thus permit substantially continuous use of the apparatus.

From the foregoing description it is thought to be obvious that an apparatus for wood distillation constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

1. A retort and furnace structure for wood distillation, comprising an outer furnace structure including a base and a top wall of arcuate cross sectional design, an upwardly opening flue leading from one end of the structure through the top wall, a retort comprising a cylindrical body extending longitudinally through the first mentioned structure and of a diameter substantially equal to the interior height of the structure, the retort resting upon and extending throughout the central portion of said base and engaging the top wall along the center thereof, that end of the retort remote from the flue end of the structure being adapted to be opened for the introduction of material thereto, means for carrying off products of distillation from the retort, and means for introducing fuel into the furnace structure through lateral openings in the top wall thereof.

2. In a furnace and retort structure for destructive distillation, a furnace body comprising a base wall, an elongated top wall of arcuate cross sectional design resting upon said base wall and closed at the ends, a flue opening through said top wall at one end of the body, laterally extending bodies at opposite sides of the top wall and directed toward the other end of the furnace body and further having passages therethrough to permit the introduction of fuel into the furnace body, a retort comprising an elongated cyl-

inder resting upon and extending longitudinally of the furnace base wall and of a diameter to contact with the central portion of the top wall, dividing the furnace body into two 5 combustion chambers, said retort terminating in spaced relation to that end wall of the furnace body adjacent the flue and projecting through the opposite end wall, means for introducing material into the projecting end of 10 the retort, and means communicating with the interior of the retort for conducting distillation products therefrom.

3. A furnace and retort structure for wood distillation, comprising a furnace structure 15 having a base provided with a longitudinally extending centrally arranged raised portion, an arcuate wall upon said base forming the furnace chamber, the chamber having said raised portion extending centrally there- 20 through, a lead-off at one end of the furnace structure, a retort in the form of a cylindrical body arranged centrally within the cham- 25 ber and extending longitudinally thereof upon the raised portion of said base, said chamber having each end closed and said retort having one end accessible through a closed end of the chamber, a lead-off for said retort, means for introducing material there- 30 into, and means for introducing fuel into the furnace chamber, comprising a pair of obliquely directed structures formed upon the base at the end of the furnace structure re- 35 mote from the lead-off therefor, each of said structures having the passage extending therethrough and directed into the furnace structure toward the lead-off therefor.

In testimony whereof, we hereunto affix our signatures.

FRANK BRASS.
NOAH OTTEN.
GEORGE C. TOLAND.
